PAUL H. DARRAH, OF LOS GATOS, CALIFORNIA

WATER WHEEL

Application filed July 19, 1930. Serial No. 469,088.

My invention relates to improvements in water wheels and it consists in the combinations, constructions, and arrangements hereinafter described and claimed.

5 An object of my invention is to provide a water wheel designed to be disposed in a stream bed. Novel means is provided for making the wheel inoperative while yet permitting the water to flow through the device. 10 Another feature of the device lies in the novel manner of dropping paddles in the path of the stream and then of subsequently lifting the paddles out of the stream so that the paddles, in their return movement, will not interfere with the flow of water in the stream.

Other objects and advantages will appear in the following specification, and the novel features of my invention will be particularly pointed out in what I hereinafter claim.

20 My invention is illustrated in the accompanying drawings forming a part of this application, in which

Figure 1 is a top plan view of the device with a portion of the casing removed to show 25 the water wheel.

Figure 2 is a section along the line 2—2 of Figure 1.

Figure 3 is a section along the line 3—3 of Figure 1.

30 Figure 4 is a perspective view of one of the paddles.

Figure 5 is a perspective view of a part of the device.

Figures 6 and 7 are sections along the lines 35 6—6 and 7—7 of Figure 1.

Figures 8 and 9 are side and end views of a paddle.

Figure 10 is an underside view of a cover board.

40 In carrying out my invention I provide a casing indicated generally at 1. This casing has an inlet 2 for water, and this inlet is narrowed down at 3 for guiding the water to a compartment 4 at one side of the compartment. The compartment 4 has an open end, as at 5, for allowing the water to flow from the compartment back into the stream or other water source.

45 A water wheel is mounted within the compartment 4. I will first describe how this

wheel operates when impelled by water, and then I will set forth the novel means for causing the wheel to become inoperative and yet at the same time permit the water to flow through the device.

55 A central, vertical shaft 6 is mounted in the compartment 4 and journaled in the bottom of the casing, as at 7, and in a removable cover board 8. The shaft 6 has a hub portion 9 that in the present form of the device is 60 shown hexagonal in shape.

In Figure 1 it will be noted that I provide for rods 10 that are disposed midway between the edges of the faces 11 on the hub 9 and adjacent to the tops of these faces. The rods 65 10 project at right angles to the faces 11 and have their outer ends connected to each other by members 12 of the shape shown in Figure 5. Figure 4 shows how the members 12 are connected to the rods 10 and further shows 70 how a water paddle 13 is swingably mounted on each rod 10. The face 11 carries a bracket 14 that limits the movement of the paddle 13 in one direction. The bracket 14 holds the paddle in a vertical position.

75 The water wheel is designed to rotate in a clockwise direction, when looking at Figure 1. The paddles 13 depend vertically; the water impinges against these paddles and causes them to turn the wheel and the shaft 6. The 80 brackets 14 hold the paddles 13 in a vertical position as the paddles pass around the top of the water wheel, as shown in Figure 1.

I provide novel means for raising the paddles out of the water after they have done 85 their work and for causing the paddles to re-enter the water when the cycle is again started. For example, from the position A to the position B the paddles 13 extend downwardly at right angles and are acted upon by the water. When the paddles leave the position B they will be raised into a position overlying the water and will be maintained in this position until they again leave the point A.

90 The means for accomplishing this comprises a cam 16, shown in Figures 1 and 6, that engages with the paddles 13 and lifts them so that they will swing about the rods 10. Lugs 15 are carried by each paddle 13, and these lugs ride upon a curved arm 17 (see 100

Figure 6), after the paddles 13 have been partially swung about the rods 10. The arm 17 merges into a ring shaped member 18. In Figure 1 I show how the lugs 15 are supported by the ring 18. The lugs in turn hold the paddles 13 in the horizontal position shown in Figure 1.

The ring 18 is broken at 19 and a swingable ring segment 20 normally inclines downwardly from the ring 18 and permits the lugs 15 to ride down and thus to lower the paddles 13 into a vertical position where they may be again acted upon by the water.

It will be seen from the construction that the paddles are lowered for a portion of their movement and are raised for the remaining portion of this movement. This prevents the paddles from dragging through the water on their return movement.

If it is desired to cause the water wheel to become inoperative, the ring segment 20 (see Figures 1 and 7) may be shifted from its downwardly inclined position into a position where it will bridge the gap 19. The lugs 15 will now continue to ride upon the ring 18 and will prevent the paddles 13 from again dropping back into the water. Figure 7 shows how the ring segment 20 is mounted upon a stub shaft 21 and further shows how this stub shaft is rocked by means of a handle 22. A swinging of the handle 22 into a vertical position will move the segment 20 into a position to bridge the gap 19. When it is again desired to cause the water wheel to operate, the handle 22 may be swung into the full line position shown in Figure 7 and the shaft 6 may be manually rotated a distance sufficient to cause one of the paddles 13 to drop into the water and to be impelled thereby. The water striking this paddle will swing the water wheel and will cause the other paddles to successively drop into the water. The handle 22 may be held in a vertical position by a hook 23 shown in Figure 1. The shaft 6 is connected to any device that it is desired to operate. The weight of the shaft and the water wheel may be carried by a thrust bearing 24, shown in Figure 2. The device is simple in construction and durable and efficient for the purpose intended.

Although I have shown and described one embodiment of my invention, it is to be understood that the same is susceptible of various changes and I reserve the right to employ such changes as may come within the scope of the invention as claimed.

In Figures 3 and 6, I show a partition 25 for directing the water past one side of the water wheel; while in Figures 3 and 10, I show the cover 8 provided with an annular groove 26 for receiving the lugs 15, when the latter are supported by the ring 18.

I claim:

In a water wheel construction, a rotatable wheel having paddles swingably carried

thereby, a ring disposed in concentric relation with the wheel and having a portion thereof removed, means for swinging the paddles into a position overlying the ring, a swingable segment for bridging the gap in the ring 70 and allowing the paddles to pass thereover, an operating handle extending from the segment having a limited swinging movement, and a hook-shaped member arranged for engaging with the handle and adapted for holding the segment in bridging relation with the ring ends.
